(57) **CLAIM**

The ornamental design for a rear lid for toilet, as shown and described.

DESCRIPTION

FIG. 1 is a front elevation view of a rear lid for toilet showing the new design;

FIG. 2 is a rear elevation view thereof;

FIG. 3 is a left side elevation view thereof;

FIG. 4 is a right side elevation view thereof;

FIG. 5 is a top plan view thereof; and,

FIG. 6 is a perspective view thereof.

The bottom of the product incorporating the design is barely visible or invisible, so the bottom view is omitted.

The broken lines represent portions of the rear lid for toilet and form no part of the claimed design.
